UNITED STATES PATENT OFFICE.

MANFRED REIFFENSTEIN, OF VIENNA, AUSTRIA.

WATER-POWER ENGINE.

Application filed June 19, 1925, Serial No. 38,333, and in Austria July 2, 1924.

In the known impulse turbines (Pelton-wheels) the specific speed amounts to about 5 to 6 revolutions (ft.=lb. units) if the water is supplied by a single nozzle. A greater specific speed cannot be obtained with the aid of one nozzle only, as the jet would have to be too thick compared with the diameter of the runner and thus would unfavourably influence the efficiency. Therefore in the 10 case of greater quantities of water a number of nozzles, if necessary a number of runners disposed side by side on a shaft, are provided. The specific speed increases in proportion with the square root of the number 15 of nozzles, and therefore amounts to 10 to 12 only in the event of four nozzles. In this resides the principal obstacle against the employment of the impulse wheels, in the event of larger quantities of water and 20 smaller heads. These drawbacks are removed by the water power engine according to the present invention.

The essential feature of the present invention is that a whirl-stream of annular cross-section and concentric to the runner, strikes upon the entire circumference of the said wheel on entering it, the annular cross-section of the said whirlpool stream corresponding to the annular entry area covered 30 by the admission-edges of the vanes of the runner.

Further, the present invention relates to the production of the whirl-stream, which is accomplished by a spiral-casing, in which a 35 whirling motion is imparted to the water by means of a tangential entry, the inner layers of the annular whirlpool thus formed flowing off over the edge of a circular orifice provided in the side wall of the spiral casing 40 concentric to the whirlpool.

Several modes of carrying out the present invention are shown by way of example on the accompanying sheet of drawings in which:—

45 Figs. 1 and 2 are diagrammatic views in longitudinal section and transverse section respectively through the casing.

Fig. 3 shows diagrammatically a construction of the subject matter of invention.

50 In the construction shown in Figs. 1 and 2, the casing consists of two plane side-walls 1 and 2 and a spirally shaped cover 3, the water being tangentially introduced into the said casing through an inlet pipe 4 and 55 guided in a circular path by the cover 3. In the casing circulates the water in the manner

of a proper whirlpool, as the inner flow lines of the whirlpool have a greater revolving velocity than the outer flow lines of the same, thus the product resulting from the axial distance of each flow line and its revolving speed is constant. Therefore there is a certain axial distance within which water is not flowing. Thus the inner cylindrical space is free of water. 60 65

Owing to the steadily incoming water the inner diameter of the whirlpool annulus becomes gradually smaller until it passes below the diameter of the circular orifice 5 in the side wall 2. Now the water flows off in an annular cross section over the edge of the circular exit with the tangential speed C_t at an axial speed c_a . Each flow line is directed tangentially with respect to the circular outlet orifice as shown in Fig. 1. The axial speed causes the flow line to be directed at an angle α with respect to the casing-wall containing the outlet orifice. The tangentially and angularly directed flow lines form a single-cased hyperboloid which however, as shown in Fig. 2, is slightly altered in shape by gravitation. The actual exit speed 70 75 of each flow line is equal to the spouting velocity adjoined to the head less small losses of friction. 80 85

The runner 7 (Fig. 3) is disposed in the same axis with the whirlpool, the vanes or buckets being of particular shape.

The water leaving the runner has the following characteristic shapes during the different conditions of running: 90

1. *No-load running.*—The body of water maintains its hyperbolic shape, as if a wheel were not present.

2. *The wheel is stopped.*—The whirlpool 95 deflected by the fixed buckets of the wheel, forms a body, which is sub-divided by the vanes and reversed in comparison to the previous whirlpool stream.

3. *The proper speed.*—The whirl-stream is 100 deflected in the axial direction by the vanes of the running wheel and leaves the latter as an inert trunnion (plait) of water extending in the axial direction and clearly being wound in the one or other sense if the 105 normal speed is exceeded or not reached.

The regulation of the flow is effected by reduction of the gate opening (throttle needle or the like in the entry 4). Thereby the consumed quantity of water Q and the 110 axial exit speed c_a are varied, while the absolute exit velocity c remains unaltered. The

wall-thickness of the whirl-stream becomes smaller and the exit angle α of the current strings more acute, whereby the efficiency is also very favourable at part gates.

5. The water power engine can be built with horizontal or vertical shafts. Instead of one inlet 4 only, also a number of inlet-pipes may be arranged in a circle. Further the exit from the casing may be disposed not 10 only at the broadside as shown in Figs. 1 and 2, but may be arranged if desired at the spiral cylindrical mantle thereof by means of a slit provided in the latter. The runner may be arranged in such a manner, that the 15 water passes the vanes not axially as shown in Fig. 3 but essentially in a radial direction.

Thus the water power engine according to the present invention has the following peculiarities and advantages:

- 20 1. A great flow at a high speed and therefore the possibility of applying the favourable impulse wheel at small heads from 2 metres onward and at large quantities of water.
- 25 2. Simple and inexpensive construction, dispense of any guide-apparatus, guide vanes, etc.

3. Reduction of the losses due to water friction, as neither nozzles nor guide-vanes are applied.

4. A non-dropping efficiency at part gates.

5. Simplest regulation by an adjusting-needle or the like.

I claim:

1. In a water power engine a rotor, means 35 for positively producing a vortex of liquid with inner free cylindric space and of annular cross-section and for delivering said vortex axially towards said rotor.

2. In a water power engine, a rotor, means 40 forming a vane free spiral conduit for positively producing a hollow vortex of liquid with inner free cylindric space and annular cross-sectional shape and for delivering said vortex axially towards said rotor.

45 3. In a water power engine the combination of a rotor comprising vanes formed to freely discharge the water, with means forming a vane free spiral conduit for positively producing a vortex of water with inner free 50 cylindric space and for delivering said vortex axially towards said rotor.

In testimony whereof I affix my signature.
MANFRED REIFFENSTEIN.
